UNITED STATES PATENT OFFICE.

ELBERT J. LANGLEY AND EDWARD FOLEY, OF LOS ANGELES, CALIFORNIA.

DESIGN FOR A GARMENT-HANGER.

48,067.

Specification for Design.

Patented Nov. 2, 1915.

Application filed May 4, 1915. Serial No. 25,840. Term of patent 3½ years.

To all whom it may concern:

Be it known that we, ELBERT J. LANGLEY and EDWARD FOLEY, both citizens of the United States of America, and both residing in the city of Los Angeles, county of Los Angeles, State of California, have invented a new, original and ornamental Design for a Garment-Hanger, of which the following is a specification, reference being had to the accompanying drawings, forming part hereof, and in which—garment hanger, illustrating our new design; Fig. 2 is a top plan view of the same; and Fig. 3 is a bottom plan view of the same.

We claim:

The ornamental design for a garment hanger, as shown.

ELBERT J. LANGLEY.
EDWARD FOLEY.
